UNITED STATES PATENT OFFICE.

JAMES ROBERT MOORE, OF TARRYTOWN, NEW YORK, ASSIGNOR OF ONE-HALF TO
CHARLES L. CASSIDY, OF NEW YORK, N. Y.

HEADLIGHT.

1,398,973.

Specification of Letters Patent. Patented Dec. 6, 1921.

Application filed May 17, 1918. Serial No. 235,136.

To all whom it may concern:

Be it known that I, JAMES ROBERT MOORE, a citizen of the United States, and a resident of Tarrytown, county of Westchester, and 5 State of New York, have invented a certain new and useful Improvement in Headlights, of which the following is a specification.

The invention relates to headlights for vehicles, and more particularly for automobiles, although it will be understood that the 10 invention may be carried out in connection with other devices such as locomotives and trolley cars.

The object of the invention is to produce a 15 headlight by means of which no light rays will be so thrown as to interfere with the vision of persons using the road.

A further object is to construct the device so that all of the light from the source will 20 be utilized to illuminate the roadway and vicinity.

A further object is to provide a device for the purpose specified which may be easily attached to existing apparatus.

25 These and further objects will more fully appear in the following specification and accompanying drawings considered together or separately.

One embodiment of the invention has been 30 illustrated in the accompanying drawings, in which like parts in all of the several figures are designated by similar reference characters, and in which—

Figure 1 is a longitudinal sectional view 35 of an automobile head light embodying the invention, the section being taken on the line 1—1 of Fig. 2.

Fig. 2 is a front elevation of the device.

Fig. 3 is a horizontal section taken on the 40 line 3—3 of Fig. 1.

Fig. 4 is a front elevation of a modification, and

Fig. 5 is a longitudinal section of a further modification.

45 In Figs. 1, 2 and 3 the invention is shown as an attachment for use in connection with existing forms of headlights. In this embodiment of the invention 1 designates a reflector, 2 the source of illumination, 3 the 50 glass front and 4 the annulus for retaining the glass in position. The lamp 2 is located in the horizontal center of the reflector and the socket 5 extends through the reflector and has attached thereto the leading in 55 wire 6.

Carried within the reflector 1 is an auxiliary reflector 7 which partially surrounds the lamp 2. This auxiliary reflector surrounds the lamp to such an extent as to intercept all rays of light emanating from the 60 lamp below the plane of the horizontal center and prevent such rays from reaching the parabolic reflecting surface below the plane of the focal center of such reflector.

The auxiliary reflector 7 is preferably in 65 the form of a cylindrical trough with its concave or inner surface highly reflective. The rear end of the trough is inclosed by means of a wall 8 which is shaped to conform to the configuration of the apex of the 70 reflector 1. The wall 8 is provided with an open ended slot 9 through which the socket of the lamp projects and will permit ready removal of the auxiliary reflector 7.

In the front end of the reflector 7 in line 75 with the focal axis of the reflector 1 and in proximity to the glass 3 is carried a screen 10 preferably of semi-transparent or opalescent character. The screen 10 may, however, be of opaque material if desired. The screen 80 may be secured to the trough in any desired manner or it may be attached to or form a part of the glass 3. In the drawings, Figs. 1, 2 and 3 the screen is illustrated as provided with a frame 11 secured to the trough 85 7 and surrounding the edges of the screen but it will be understood that the screen may be secured in place by other means and that the frame may be omitted if desired.

Carried by the trough 7 or frame 11, as 90 the case may be, are spring arms 12, 12 which bear against the inner side of the glass 3 and serve to retain the reflector 7 in position against the reflector 1 and to prevent rattling. The ends of the spring arms are 95 preferably provided with elastic pads 13 to prevent injury to the glass.

In the embodiment of the invention illustrated in Figs. 1, 2 and 3 two arms 14, 14 are carried by the trough 7. Each arm 14 carries a movable extension 15 provided with a foot 16 for engagement with the reflector 1. These arms will support the auxiliary reflector 1 when the glass 3 is removed and may be dispensed with if desired.

The auxiliary reflector is illustrated as having a plain cylindrical inner surface but it is desired to have it understood that said reflecting surface may be of any desired form or type.

105

110

The screen 10 may be of any desired shape. It may be a simple disk to prevent the unobstructed passage of direct rays from the lamp but preferably it is of approximately the shape illustrated which will prevent the unobstructed passage of rays reflected from that portion of the wall 8 which lies below the horizontal center of the lamp.

If the screen be of opaque material its inner surface will be highly reflective and so disposed that light reflected from it will be directed to the upper half of the main reflector and thence forward and downward.

In Fig. 4 is illustrated an improved form of headlight. In this embodiment of the invention the main reflector is in the form of a semi-paraboloid. Viewed from the front this reflector 17 appears as a semi-circle. The auxiliary reflector 18 may be integral with the reflector 17 and the plane surfaces 19 connecting the two reflectors may be of such a nature that they will not reflect light or they may be so constructed that any light reflected from them will be reflected back to the main reflector and thence outward and downward.

The screen 10² may be an area of the front glass which has been rendered non-transparent by sand blasting or otherwise or it may be a separate piece of material of non-transparent character cemented or otherwise secured to the front glass.

In operation rays from that portion of the source above the horizontal axis will encounter the upper half of the parabolic reflector 1 and be reflected forward and downward. Rays emanating from the lamp below the horizontal axis will be reflected from the auxiliary reflector 7 to the upper part of the reflector and thence forward and downward. Light reflected from that portion of the wall 8 of the reflector 7 below the axis will be in part caught by the main reflector and in part be intercepted by the screen 10, which latter will also intercept direct rays from the lamp.

As shown in Fig. 5 the screen 20 and auxiliary reflector 21 may be made integral and secured to a stationary portion of the headlight. The figure shows a spring arm 22, one of a pair, by means of which the device may be attached to the lamp bulb.

The auxiliary reflector may be so proportioned and arranged that none of the direct rays from the source will pass through the glass 3.

All of the light from the lamp will issue from the headlight, all of it will be reflected forward and none of it will be reflected in an upward direction but will be

directed to the surface of the road. Those rays which pass through the semi-transparent screen will be so softened as to be unobjectionable.

In accordance with the provisions of the patent statutes, the principle of the invention is described, together with the apparatus which is considered to represent the best embodiment thereof, but it is desired to have it understood that the apparatus shown is merely illustrative, and that the invention may be carried out in other ways.

Having now described the invention what is claimed and desired to be secured by Letters Patent is:—

1. A headlight comprising a casing having a parabolic inner, reflecting surface, a front for the casing, a lamp within the casing, said lamp being located in the focal axis of the reflector, a trough-shaped member below the lamp, said member having sides extending upward to approximately the focal axis of the reflector and on either side of the lamp, a screen in front of the lamp, and means for supporting the member within the casing, said means engaging the casing in proximity to the front.

2. A headlight comprising a casing having a parabolic inner, reflecting surface, a front for the casing, a lamp within the casing, said lamp being located in the focal axis of the reflector, a trough-shaped member below the lamp, said member having sides extending upward to approximately the focal axis of the reflector and on either side of the lamp, a screen in front of the lamp, means for supporting the member within the casing, and spring arms carried by the member and engaging the front.

3. A headlight comprising a circular casing having a parabolic inner, reflecting surface, a front for the casing, a lamp within the casing, said lamp being located in the focal axis of the reflector, a trough-shaped member below the lamp, said member having sides extending upward to approximately the focal axis of the reflector and on either side of the lamp, a screen carried by the member in proximity to the front, said screen extending upward radially from the center toward the periphery of the casing and diminishing in width toward its upper end, and means for supporting the member within the casing.

This specification signed and witnessed this seventh day of May, 1918.

JAMES ROBERT MOORE.
